UNITED STATES PATENT OFFICE.

THOMAS DE LA MARE, OF TOOKE, UTAH.

HAY-DERRICK.

SPECIFICATION forming part of Letters Patent No. 727,104, dated May 5, 1903.

Application filed December 20, 1902. Serial No. 136,027. (No model.)

To all whom it may concern:

Be it known that I, THOMAS DE LA MARE, a citizen of the United States, residing at Tooele, in the county of Tooele and State of Utah, have invented a new and useful Hay-Derrick, of which the following is a specification.

This invention relates to that class of devices known as "hay-derricks" and which are used for the purpose of unloading hay from a wagon and piling or stacking the same where desired, said device being used in connection with an ordinary hay fork, sling, or grapple.

My invention has for its object to provide a device of this class which shall be simple in construction, stout and durable, so as to be capable of handling heavy loads with ease and celerity, the construction being also such as to enable a stack of large size to be built when the size of the machine is taken into consideration.

A further object of my invention is to so construct the machine that certain parts thereof shall be reversible, thus enabling a greater area to be covered than would otherwise be the case.

With these and other ends in view my invention consists in the improved construction, arrangement, and combination of parts, which will be hereinafter fully described, and particularly pointed out in the claims.

In the accompanying drawings, Figure 1 is a front elevation of a hay-derrick constructed in accordance with the principles of my invention. Fig. 2 is a horizontal sectional view with dotted lines indicating the reversed position of certain parts of the machine. Fig. 3 is a detail side view of the lower portion of the machine. Fig. 4 is a sectional detail view, on an enlarged scale, taken through the upper portion of the mast and the adjacent part of the jib or derrick-arm. Fig. 5 is a sectional detail view taken on the line 5-5 in Fig. 1.

Corresponding parts in the several figures are indicated by similar characters of reference.

The base of my improved derrick is composed of the sills 11, supporting the cross-pieces 22, which latter are extended beyond one of the sills to form brackets 33. An ad-

ditional cross-brace 4 is preferably arranged diagonally, as will be best seen in Fig. 2 of the drawings. This diagonal cross-piece supports the mast 5, which may be mortised therein and which is additionally supported by means of oppositely-disposed vertical braces 66; connected at their upper ends by means of a bolt 7, extending transversely through the mast, and provided at their lower ends, which are screw-threaded, with nuts 8, which are tightened up against the under side of the cross-brace 4. By this construction the lower end of the mast is connected very firmly with the cross-brace 4, and it is also well adapted to receive the transverse hinge-bolt 9, which extends transversely between the vertical braces 6 and which is held in position detachably by means of a pin 10, engaging a slot 11 in the end of said hinge-bolt. 1212 designate braces, the lower ends of which are bolted to the cross-pieces 2 and the upper ends of which are connected with the mast by means of a transverse bolt 13. 1414 are inclined braces, the lower ends of which are bolted to the cross-pieces 22 and to the front sill 1, while their upper ends embrace the mast and are connected in rear of the latter by means of a bolt 15. An additional bolt 16 is curved and extends through the braces 14 and through the mast 5, which is thus sustained firmly and rigidly in an upright position.

The upper end of the mast is provided with a thimble or ferrule 17, the upper side or face of which may be provided with an annular groove 18, forming a ball-race, in which may be placed antifriction-balls 19 to reduce the friction between the said ferrule and the revolvable cap 20. The latter is provided on its upper side with lugs or ears 21, receiving between them a casting 22, which is mounted pivotally between the lugs 21 by means of a bolt 23. The casting 22 is provided with laterally-extending flanges 24, the upper faces of which are concaved to support the derrick-arm or jib 25, which is bolted to or otherwise suitably connected with said flanges. The said casting 22 is also provided with oppositely-extending ears or lugs 26, through which extend the lower ends of eyebolts 27, the upper ends of which receive a bolt 28, extending transversely through a brace-rod 29, which is thus

firmly supported upon the derrick-arm and which serves to support the truss-rod 30, the ends of which are suitably connected with the ends of said derrick-arm. The latter is 5 thus braced and enabled to support heavy loads.

The lower end of the derrick-arm is provided with straps 31, having perforations 32 for the reception of a pin or bolt 33, by means 10 of which adjustable connection may be made with the hinged brace-rod 34, which is provided with a plurality of transverse perforations 35 for the reception of the connecting pin or bolt 33. The lower end of the brace 34 15 has a strap 36, which is connected, by means of a link 37, with the hinge-bolt 9, which latter is provided with an eye for the reception of the pivot-pin or pintle. The brace 34, it will thus be seen, is thus not merely hinged, 20 but has a link connection with the hinge-bolt, whereby it is enabled to move freely and whereby the range of its movement is increased. The brace-rod 34 is provided with a latch 38, one end of which is secured to the 25 under side of said brace, while its opposite end extends through a perforation therein and is connected with the latch-rope 39. The latch member 38, which constitutes a spring-latch, is adapted to engage a catch 40, which 30 is bolted detachably to the braces 12 and 14 on either side of the machine, so that it may be moved from one side to the other. For convenience one of the catch members may be secured permanently to the braces at each 35 side of the machine when desired.

The hoisting-rope 41, carrying the hoisting element 42, which may be of any desired construction and which, as already stated, may be a sling, a fork, or of any description, has 40 one end attached at 43 to the upper end of the derrick-arm, passing from thence under the pulley 44, supporting the hoisting element, and over a plurality of suitably-arranged guide-pulleys 45 to the point at which the 45 draft is attached. Suitably connected with the hoisting-rope, at any desired point thereof, is the latch-rope or trip-rope 39, which passes through suitable guides 46 to the latch, with which it is connected. It is obvious that the 50 time of tripping the latch may be regulated by lengthening or shortening the trip-rope.

From the foregoing description, taken in connection with the drawings hereto annexed, the operation and advantages of my invention 55 will be readily understood. When a loaded wagon is driven up in front of the derrick, the hoisting element is engaged with the load, after which by applying power to the draft-rope the load connected with the 60 hoisting element will be elevated until the trip-rope is rendered sufficiently taut to trip the latch, when by continuing the draft the derrick-arm will be swung to the position at which it shall be desired to drop the load, the 65 dropping being effected by means of a trip-rope 50, leading from the hoisting element to a point within convenient reach of the oper-

ator. When the draft-team is backed, the draft-rope may be restored manually by pulling upon the trip-rope 50, and the derrick 70 may also be manually restored until the latch is in engagement with the catch. By simply reversing the position of the hinge-bolt 9, as shown in dotted lines in Fig. 2, and transferring the catch member 40 to the opposite 75 side of the machine the initial position of the derrick-bar may be reversed, as will be readily understood, and by providing suitably-disposed guide-pulleys for the draft-rope and the trip-rope the draft may be applied 80 at the opposite side of the machine, thus rendering it unnecessary to swing the derrick through more than half the space that would otherwise be required. This is considered a great convenience and saving of time and 85 labor.

In building the stack a quantity of the hay will be deposited upon the projecting ends or brackets 3 of the cross-pieces 2 of the frame. The latter is thereby sustained in position 90 and prevented from tilting. The ends of the sills are preferably provided with perforations, through which stakes may be driven into the ground for the purpose of assisting in retaining the device in operative position. 95

My improved hay-derrick while simple in construction and capable of being erected at a moderate expense is capable of handling heavy loads in a very rapid and satisfactory manner, and its working capacity is greatly increased by the means which I have provided for reversing the initial position of the derrick-bar, whereby the distance required to be traveled by the hoisting-team is greatly reduced. 105

The general construction of the device has been designed with a view to strength and rigidity. Especially do I consider the means for bracing the mast and for mounting the derrick-bar of no little importance. The 110 casting that supports the derrick-bar also serves, by means of the eyebolts 27, engaging the truss-brace, to sustain the latter, and I am enabled by the general construction herein described to use lighter and less expensive 115 material than would otherwise be required in order to resist the strain to which the device will in practice be subjected.

While I have in the foregoing described a simple and preferred form of my invention, 120 I desire it to be understood that I do not limit myself to the precise structural details herein set forth, but reserve the right to any changes and modifications which may be resorted to without departing from the spirit and scope 125 of my invention.

Having thus described my invention, I claim—

1. In a hay-derrick, a base having a cross-piece, a mast supported upon said cross-piece, 130 braces extending vertically through the latter adjacent to the mast, a bolt extending transversely through the mast and connecting said braces, and a hinge-bolt extending

transversely through the mast between said braces.

2. In a hay-derrick, a base having a cross-piece, a mast mortised in said cross-piece, 5 braces having screw-threaded lower ends extending through said cross-piece adjacent to and on opposite sides of the mast, a bolt extending transversely through the mast and connecting the upper ends of said braces and 10 tightening-nuts at the lower ends of the latter.

3. In a hay-derrick, a base having a cross-piece, a mast mortised in said cross-piece, braces having screw-threaded lower ends extending through said cross-piece adjacent to 15 and on opposite sides of the mast, a bolt extending transversely through the mast and connecting the upper ends of said braces, tightening-nuts at the lower ends of the latter, and a hinge-bolt extending transversely 20 through the mast between the braces and below the bolt connecting said braces.

4. In a hay-derrick, a base comprising sills, parallel cross-pieces and a diagonal cross-piece, a mast supported upon the latter, inclined braces having their lower ends secured 25 at the junctions of the parallel braces with the front sill, means connecting the upper ends of said braces in rear of the mast, and a curved bolt extending through said mast 30 and braces.

5. In a hay-derrick, a base comprising sills, parallel cross-pieces and a diagonal cross-piece, a mast supported upon the latter, inclined braces having their lower ends secured 35 at the junctions of the parallel braces with the front sills, means connecting the upper ends of said braces in rear of the mast, a curved bolt extending through said mast and braces and auxiliary braces connecting the 40 mast with the parallel braces of the base.

6. In a hay-derrick, a mast, a derrick-arm swiveled at the upper end of said mast, a brace-rod connected with the lower end of said derrick-arm, and a link connecting the 45 lower end of said brace with the mast near the lower end of the latter.

7. In a hay-derrick, a mast, a derrick-arm swiveled at the upper end of said mast, a brace-rod connected pivotally and adjustably 50 with the lower end of said derrick-arm, and a link connecting the lower end of said brace-rod with the mast near the lower end of the latter.

8. In a hay-derrick, a mast, a derrick-arm 55 swiveled at the upper end of said mast, a brace-rod connected pivotally and adjustably with the lower end of said derrick-arm, a

hinge-bolt extending detachably and reversibly through the mast near the lower end of the latter, and a link connecting said hinge-bolt with the lower end of the brace-rod. 60

9. In a hay-derrick, a mast, a derrick-arm swiveled at the upper end of said mast, a brace-rod connected with the lower end of said derrick-arm, a hinge-bolt extending detachably and reversibly through the mast near 65 the lower end of the latter, a link connecting said hinge-bolt with the lower end of the brace-rod, a spring latch member connected with the latter, and a suitably-disposed catch 70 adapted to be engaged by said spring latch member.

10. In a hay-derrick, a mast, a cap swiveled at the upper end of said mast and having upward-extending lugs, a casting supported hingedly between said lugs and having laterally-extending concaved flanges and oppositely-extending perforated lugs, a derrick-arm supported upon said casting and the flanges thereof, a truss-brace, brace-bolts 80 connecting the latter with the perforated lugs of the casting, and a truss-rod supported by the truss-brace and connected with the ends of the derrick-arm. 85

11. In a hay-derrick, a base, a mast supported thereon, inclined braces connecting said base with cross-pieces of the base, a derrick-arm swiveled at the upper end of the mast, a brace-rod connected pivotally and adjustably with the lower end of the derrick-arm, a link connecting the lower end of said brace-rod with a hinge-bolt near the lower end of the mast, said hinge-bolt being mounted reversibly and detachably, a spring latch member connected with the brace-rod, a suitably-disposed catch adapted to be engaged by said latch member, a hoisting element, a hoisting-rope attached at one end to the upper end of the derrick-arm, reeved through a pulley connected with the hoisting element 100 and through suitably-disposed guide-pulleys and leading to the draft, and a trip-rope having its ends attached respectively to the hoisting-rope and to the spring-latch connected with the brace which connects the derrick-arm with the mast, said trip-rope being guided over suitably-disposed guiding means. 105

In testimony that I claim the foregoing as my own I have hereto affixed my signature in the presence of two witnesses.

THOMAS DE LA MARE.
